UNITED STATES PATENT OFFICE

WALTER W. ROBINSON, OF BELOIT, WISCONSIN

THERMIONIC-TUBE HOLDER

Application filed June 20, 1927. Serial No. 200,063.

These improvements relate to holders for thermionic tubes. The object of the invention is to provide notably simple, cheap and effective means for holding the tube for completing circuits through the electrode terminals.

In the accompanying drawings, forming a part hereof, Figure 1 shows the construction in top plan view as applied to what may be considered for example a baseboard of a radio receiving set; Figs. 2 and 3 are sectional views on the lines 2—2 and 3—3 respectively of Fig. 1; Fig. 4 is a bottom plan view of the construction of Fig. 1; and Fig. 5 is a fragmentary bottom view with the contact member removed.

The baseboard 10 may be of insulating material but it may also be of metal. It is provided with a relatively large opening 11 on circular lines except that at diametrically opposite places 12 I prefer to leave indentations to accommodate the rivets 13 in order to reduce size and save material of parts held thereby.

Figs. 2 and 3 show that a little larger than and covering the opening 11 is a piece of sheet insulating material 14 the shape of which is shown in Fig. 4. Where the baseboard is of insulating material this element 14 might be omitted in some constructions, but it is preferably employed so as to cover the otherwise exposed parts of the contact members, to provide better finish, and to provide a plate through which definitely-sized holes may be made for the tube terminals. A group of four relatively small holes 15 (Fig. 1) are formed in the insulation 14, which holes respectively accommodate the grouped electrode terminals which as is well understood, are in the form of pins projecting in parallel arrangement from the base of the tube and may vary in diameter to determine the proper orientation of the tube in the device.

On the insulation 14 is positioned another piece of sheet insulating material 20 the shape of which suitably conforms to that of the insulation 14, as shown by Fig. 4; but it is preferably slightly smaller. This piece 20 may be of hard rubber, fibre or other hard

and strong sheet insulating material. Four holes 21, elongated outwardly as shown by Fig. 5, are made in the sheet 20, the inner ends of which register with the respective holes in the part 14, or conform to the group 55 arrangement of the tube terminals, whereby the electrode terminal pins may pass through both the plates 14 and 20. The outer wall 22, Fig. 5, of each of the elongated holes 21 is formed on straight-across lines to provide 60 a good seat for the spring member associated with it. These elongated holes are directed toward and come substantially close to marginal portions of the plate 20.

Fig. 3 shows how the leaf spring contact 65 members 23 are bent to provide a leaf 24 extending normally downward and inward into the path of the tube terminal, the metal passing through the elongated hole 21 and in contact with the edge 22 of the plate 20 70 (Fig. 5), passing thence around marginal parts of the plate 20 and being crimped tightly upon the upper and lower surfaces thereof, the spring material extending thence downward and outward again to form a projecting end 25 forming a recess 26 adapted to accommodate a wire end for attachment to this spring contact element 23. This free end 25 may be pressed tightly upon a wire as 30 and solder applied. Each of the four contact 80 members 24 is formed and held in place in the manner just described.

All of the holes mentioned, whether in the base-board or in the other elements, may be made by punching, and, with respect to each 85 piece, by a single operation. In my practice the spring members are formed by machinery and are crimped upon the member 20 around the marginal edge at the openings 21 respectively by means of a power press, and these 90 members are thus held together very rigidly. The arrangement of the contact members shown is advantageous from the standpoint of manufacture. As noted from the drawings, which are substantially to scale, the 95 spring members 24 have substantial width and will have such suitable thickness as ten to fifteen one-thousandths of an inch when made of fairly hard brass, German silver or the like.

The parts being punched and the springs secured to the member 20 the assembling is a simple matter and the two rivets 13 hold the parts securely upon the base.

5 The drawings show that this is a construction particularly designed for application to the under surface of the base, a feature which is not broadly new at this time.

10 The device is remarkably cheap in construction and assembly, and is strong and durable and highly serviceable.

I contemplate as being included herein such variations and departures from what is thus specifically illustrated and described as 15 fall within the scope of the appended claims.

I claim:

1. In a tube holder of the character described, the combination with a base of sheet material having a relatively large opening therethrough, of an insulating plate larger than and overlying said opening and being rigidly secured to the under surface of the base, said plate having a plurality of relatively small openings therethrough and located 25 within the area of the base openings for receiving tube electrode terminals, a leaf spring contact member crimped tightly upon said plate around the marginal edge thereof and at top and bottom of the plate adjacent to 30 each of said relatively small openings, said contact members extending into the paths of the tube terminals through said plate openings respectively, said contact members having means respectively for wire attachment 35 thereto.

2. In a tube holder of the character described, the combination with a base of sheet material having a relatively large opening therethrough, of an insulating plate rigidly 40 secured to the under surface of the base, said plate having a plurality of relatively small openings therethrough within the area of the base opening for receiving tube electrode terminals, said small openings being elongated 45 in the outward direction and terminating adjacent to a marginal edge of said plate, and a continuous leaf spring contact member crimped tightly upon upper and lower surfaces of said plate and around the marginal 50 edge thereof at each of said small openings and extending into the paths of the tube terminal through said plate openings respectively, each of said spring members having means for wire attachment thereto.

55 3. A tube holding member adapted to be secured upon a support and comprising a piece of insulating sheet material having a group of holes therethrough for grouped pin-like tube terminals, said holes being elongated toward and approaching close to marginal edges of the plate, and leaf spring contact members passing through said openings respectively and directed inwardly to engage tube terminals respectively and passing 60 around marginal material of the plate at the 65

openings respectively and being crimped upon the upper and lower surfaces of the plate, and being formed at the outer free ends respectively with means for wire attachment, another piece of sheet insulating material 70 covering said first-mentioned piece and having a group of holes therethrough and registering with said other holes respectively for the pin terminals, and means for holding said pieces together for application to a support. 75

4. In a tube holder of the character described the combination of a plate-like piece of insulating material having an opening therethrough for a tube terminal, and a contact member of thin spring metal having a 80 part thereof crimped tightly around an edge of the plate-like piece and upon both sides thereof adjacent to said opening and being in tight engagement with said plate-like piece at an edge thereof partly defining said opening, 85 said contact member having an integral leaf spring element passing through said opening and being formed and arranged to make contact with a pin-like terminal passing through said opening. 90
